AIRSHIP

Morris Medoff, Bronx, N. Y.

Application December 5, 1932, Serial No. 645,826

4 Claims. (Cl. 244—10)

This invention relates to an airship and has for an object to provide an airship or dirigible which will be easier and more economical of construction than the present type, which can be built more quickly and will be stronger than the airship now in existence.

A further object of this invention is to provide an airship which will have a wind tunnel extending longitudinally through the center thereof and wherein there will be horizontal fins or wings projecting from the side of the ship both fore and aft of the center, the elevator being attached to the rear fin while a vertical fin at the top rear will have one rudder and a stream lined gondola at the bottom rear will have a second rudder.

A further object of this invention is to provide an airship wherein the principle construction material consists of duralumin, and wherein the first fifty feet of the nose of the ship will be covered with a sheeting of duralumin to strengthen the same.

Still a further object of this invention is to provide a spider in the longitudinal panel which will receive an anchoring post for landing the airship.

A further object of this invention is to provide an airship having an improved type of ballonet, which ballonet will be substantially doughnut shaped in outline except for possibly a ninety degree sector at the bottom thereof.

Still a further object of this invention is to provide an airship which may be nine-hundred feet in length with the longitudinal tube through the center ten feet in diameter, wherein each of the wings or fins will be approximately one-hundred feet in length and twelve feet in width. The skeleton of this airship consists of eighteen equal parts, each fifty feet in length. With this construction this airship will decrease resistance fifty per cent and will increase flying speed one-hundred-and-fifty to two-hundred miles per hour.

A further object of this invention is to provide an airship of increased carrying capacity which will have a double set of passenger cabins within the skeleton between the ballonet and the skin and will have a large room longitudinally of the bottom of the ship for additional carrying capacity or freight carrying capacity.

With the foregoing and other objects in view, as will hereinafter become apparent, this invention comprises the constructions, combinations and arrangements of parts, hereinafter set forth, disclosed and shown on the accompanying drawings. In these drawings,

Figure 1 is a side elevation of the airship.

Figure 2 is a top plan view of the airship showing the location of the wings and the location of the side rudders,

Figure 3 is a rear view of the airship,

Figure 4 is a front view of the airship,

Figure 5 is an enlarged side view of the airship, the covering and the supporting braces being broken away to show the construction of same, the gas bag being shown between said braces,

Figure 6 is a sectional view taken on the line 6—6 of Figure 5, showing the T shaped supporting braces for the main supporting rings, (outer covering and braces being removed),

Figure 7 is a sectional view taken on the line 7—7 of Figure 6, showing clearly the arrangement of the T-shaped braces,

Figure 8 is a sectional view on the line 8—8 of Figure 6,

Figure 9 is a perspective view of one of the supporting braces showing clearly the shape of same,

Figure 10 is a sectional view taken through the front end of the hollow tube showing web member for fastening anchor post,

Figure 11 is a sectional view on the line 11—11 of Figure 1, and

Figure 12 is a detached elevational view of one of the ballonets.

There is shown at 15 the airship embodying this invention. This airship 15 is provided with a pair of forward wings 16 and rear wings 17, the front and rear wings being on opposite sides of the center of the airship. Elevators 18 are attached to the rear end of the rear wings 17 to assist in controlling the ship. A vertical fin 19 is provided at the upper rear of the ship and terminates in a rudder 20. Another rudder 21 is secured to a stream lined rear gondola 22 at the bottom of the ship, while a front stream lined gondola 23 is provided under the fore part of the ship. Three propellers 24 are located under each rear wing 17, being operative from motors located within the skin 45 of the ship 15.

A longitudinal tunnel 25 extends centrally of the ship from bow to stern and secured within this tunnel are two operative propellers 26 working from motors 27 which are out of the tunnel. Thus, the six propellers 24, three on each side, provide propulsion means of the ordinary type in combination with the jet propulsion provided by the two propellers 26 in the tunnel 25. In the fore part of the tunnel 25 a spider 28 is provided which receives an anchoring post 29 when the ship is being landed.

In construction, the ship is divided into eighteen sections each fifty feet in length, thus making a total of nine hundred feet for the ship. The nose section 30 is covered with a sheeting of duraluminum extending to the lining 31. Inasmuch as each section is substantially identical in construction, it will only be necessary to describe the construction of a single section. Each section consists of a set of inner rings 32 connected by angular members 33 to a set of outer rings 34. The outer rings 34 are connected together by a series of supporting members 35. At the end of each section, the outer rings 34 are connected by a series of supporting braces 36 to the tunnel 25. 10 As will be observed from Figures 5 to 9 inclusive, all the constructural members made of duraluminum are T-shaped in cross section, while the supporting braces 36 are composed of two T-shaped members 37 and 38 placed back to back, 15 thus making this member substantially cross shaped in cross section.

A separate balloonet 39 is provided for each section, being retained therein between the inner ring 32, the tunnel member 25, and the brace supports 36 at each end of the section. The balloonet 39 is substantially doughnut shaped in outline except for a lower sector approximately ninety degrees omitted therefrom to provide space for storage, freight or passengers, or dining room in the airship. These dining rooms, etc. are shown at 40 and separated by a cat walk 41. Another cat walk 42 is provided longitudinally of the ship between the inner and outer ring of the skeleton and extends from one end to the other, suitable side cat walks being provided where necessary. 20 Two separate passenger cabins 43 and 44 are provided on each side of the ship within the skeleton, one pair of separate cabins 43 being above the horizontal mid-point and the other pair being below the horizontal mid-point, the skeleton being covered with the skin 45 through which windows 46 are provided for each of the cabins.

At the bottom of the ship beneath the dining room 40, the ballast tanks and fuel tanks 47 are provided. In operation, the propellers 26 in the tunnel 25 serve to direct a blast of air through the tunnel giving the effect of jet propulsion to the ship, while the propellers 24 outside the skin 45 serve to assist the propulsion of the ship in the usual manner, it being noted that these propellers 24 may be made tiltable in the well known manner. With the assistance of the wings 16 and

17, each of which is substantially one hundred feet in length the ship is kept more stable and under easier control, and is capable of a speed from a hundred and fifty to two hundred miles per hour.

The novel features and the operation of this device will be apparent from the foregoing description. While the device has been shown and the structure described in detail, it is obvious that this is not to be considered limited to the exact form disclosed, and that changes may be made therein within the scope of what is claimed, without departing from the spirit of the invention.

Having thus set forth and disclosed the nature of this invention, what is claimed is:

1. An airship, a wind tunnel extending longitudinally through said airship, an anchor receiving spider entirely within said tunnel adjacent the nose of said ship.

2. An airship, a wind tunnel extending longitudinally through said airship, an anchor receiving spider entirely within said tunnel adjacent the nose of said ship, and a duraluminum sheathing on the nose of said ship.

3. An airship including a structural member, 25 said structural member comprising an outer ring T-shaped in cross section, the stem of said T pointing toward the center of said ring, a plurality of braces lying along the radii of said ring, each brace member comprising two separate 30 members, each separate member being substantially T-shaped in cross section, the stem of said latter T extending in opposite direction whereby said brace member is substantially cross shaped in cross section, the ring end of said braces 35 having its T-head spaced apart to embrace the T stem of said ring, and a flange at the other end of each brace forming a ring section parallel to said ring.

4. An airship including a framework, said framework including a plurality of spaced apart alternate internal and external ring members, girder members securing said external ring members together, said external and internal ring members each being T-shaped in cross section, 45 the T-stem of said external ring member pointing inwardly from said ring member, the T-stem of said internal ring member pointing outwardly from said internal ring member, and angular brace members securing each internal ring member to a pair of adjacent external ring members.

MORRIS MEDOFF.
